attorney.

UNITED STATES PATENT OFFICE.

GEORGE M. CÔTÉ, OF PITTSBURG, PENNSYLVANIA.

RAIL-SUPPORT.

No. 839,456.

Specification of Letters Patent.

Patented Dec. 25, 1906.

Application filed September 17, 1906. Serial No. 334,996.

To all whom it may concern:

Be it known that I, GEORGE M. CÔTÉ, a resident of Pittsburg, in the county of Allegheny and State of Pennsylvania, have invented a new and useful Improvement in Rail-Supports; and I do hereby declare the following to be a full, clear, and exact description thereof.

My invention relates to rail-supports, and has special reference to railway-ties and supports for holding the rail in place.

The object of my invention is to provide a cheap, simple, and efficient form of a rail-support which will hold the rail in place, can be easily manufactured, and can be easily and quickly assembled.

My invention consists, generally stated, in the novel arrangement, construction, and combination of parts, as hereinafter more specifically set forth and described, and particularly pointed out in the claims.

To enable others skilled in the art to which my invention appertains to construct and use my improved rail-support, I will describe the same more fully, referring to the accompanying drawings, in which—

Figure 1 is a cross-section of railroad-track, showing my invention applied thereto and with the tie partly in section. Fig. 2 is a plan view of the same with some of the parts removed from one of the rails and tie. Fig. 3 is a cross-section of the tie on the line 3 3, Fig. 1, looking in the direction of the arrow. Fig. 4 is a perspective view of the rail-clamping piece. Fig. 5 is a perspective view showing my invention applied to another form of tie.

Like symbols of reference herein indicate like parts in each of the figures of the drawings.

As illustrated in said drawings, 1 represents the rails, which are placed across the ties in the usual manner, and such ties can be of the construction shown in Figs. 1, 2, 45 and 3, which consists of a metallic hollow box-shaped tie 2, made by rolling, bending, or casting, and provided with the flat top and bottom faces 3 and 4, respectively, and the inclined sides 5.

Openings 6 lead through the top 3 of the tie 2 on each side of the base or flanges 1' on the rail 1, and within each of said openings a Z-shaped clamping-bar 7 is held by its vertical portion 7', so that its clamping end 8 rests upon the flange 1' of said rail, while its

opposite or securing end 9 fits under the top 3 of said tie. The end 9 of the bar 7 is downwardly inclined on its upper face from the vertical portion 7', as at 10, and such end is provided with a threaded hole 11 through the 60 same. A like unthreaded hole 12 is formed through the top 3 of the tie 2 opposite the hole 11 in the bar 7, and within these holes passes a threaded bolt 13, which engages with the hole 11 in the bar 7 and acts to hold 65 and secure said bar in place against the rail 1.

A locking-plate 14, formed of spring metal, fits around the bolt 13 by a hole 15 therein and between the top 3 of the tie 2 and the bolt-head 13'. This plate 14 has a flange 16 70 thereon at one end for fitting within the opening 6 and is adapted to be confined therein between the end face of the top 3 of the tie 2 and the vertical portion 7' on the bar 7, so that it is held from displacement by such 75 flange engaging with said end face. A spring-lip 17 is cut from and struck up from the plate 14, which lip is adapted to be engaged by one of the faces 13'' of the bolt-head 13' for locking the bolt 13 in place. 80

The manner of forming and assembling the parts of my improved rail-support is as follows: When the ties 2 are set in position, the rails 1 for forming the tracks are placed on the tops 3 of said ties and on that portion 85 of the said tops at the ends of the ties between the openings 6 in said ties. Each of the clamping-bars 7 is then placed in position by inserting the end 9 thereof down through the opening 6 into the tie, so that its vertical 90 portion 7' rests within said opening and the clamping end 8 rests upon the flange 1' of the rail 1. Each of the locking-plates 14 is then placed in position by inserting its flange 16 within its opening 6 and between the portion 95 7' and the edge of the tie-top 3, and then the bolt 13 is inserted through the hole 15 in the plate 14 and the hole 12 in said top, so that it engages with the hole 11 in the end 9 of the bar 7. The bolt 13 can then be screwed up 100 in said hole 11 of the bar end 9, which will act to draw said end toward the tie-top 3 and press or clamp the end 8 firmly against the rail-flange 1'. The spring-lip 17 on the plate 14 being bent up therefrom will then 105 engage with one of the faces 13'' on the bolt-head 13' and securely hold said bolt in place, while the inclined upper face 10 on the end 9 of the bar 7 will enable sufficient space to be provided between said end and the tie-top 3 110

for any further tightening up of said clamping-bar 7 in case the same becomes loose from any cause.

In Fig. 5 there is shown an ordinary **I** bar 5 or beam 18, which can be used in place of the hollow tie 2, and in such case each of the rails 1 can be clamped and secured by the bars 7 in like manner as hereinbefore described through the openings 6 in the upper flange 18' of said beam and on each side of the web 18" thereof.

Various other modifications and changes in the design and construction of my improved rail-support may be resorted to without departing from the spirit of the invention or sacrificing any of its advantages.

It will thus be seen that my improved rail-support is made up of few parts and can be easily assembled in place, while at the same 20 time the tie required can be made by rolling, bending, or casting or from commercial material, as is desired. The parts are strong and durable and are not liable to become loose or get out of order. Practically all the material used is made from commercial articles and when in place will form a firm support for the rails, as well as one in which the support will be securely held in place, and will permit further tightening up when required.

30. What I claim as my invention, and desire to secure by Letters Patent, is—

1. In a rail-support, the combination with the rail, of a tie having an opening in the same, a **Z**-shaped clamping-bar fitting in 35 said opening and having one end engaging with said rail, a bolt on said tie engaging with the opposite end of said bar for securing the same to said tie, and a plate engaging with said bolt to lock the same in position.

40. 2. In a rail-support, the combination with the rail, of a tie having an opening in the same, a **Z**-shaped clamping-bar fitting in said opening and having one end engaging with said rail, a bolt on said tie engaging with the opposite end of said bar for securing the same to said tie, and a spring-plate on said tie and engaging with said bolt to lock the same in position.

50. 3. In a rail-support, the combination with the rail, of a tie having an opening in the same, a **Z**-shaped clamping-bar fitting in said opening and having one end engaging with said rail, a bolt on said tie engaging with the opposite end of said bar for securing the same to said tie, and a plate on said tie having a spring-lip thereon for engaging with the head on said bolt to lock said bolt in position.

60. 4. In a rail-support, the combination with the rail, of a tie having an opening in the same, a **Z**-shaped clamping-bar fitting in said opening and having one end engaging with said rail, a bolt on said tie engaging with the opposite end of said bar for securing the same to said tie, and a plate on said tie and held in said opening, said plate having a

spring-lip thereon for engaging with said bolt to lock the same in position.

5. In a rail-support, the combination with the rail, of a tie having an opening in the same, a **Z**-shaped clamping-bar fitting in 7c said opening and having one end engaging with said rail, a bolt on said tie engaging with the opposite end of said bar for securing the same to said tie, and a plate on said tie and having a flange thereon for fitting in said opening, said plate having a spring-lip thereon for engaging with the head on said bolt to lock said bolt in position.

6. In a rail-support, the combination with the rail, of a tie having an opening in the 80 same, a **Z**-shaped clamping-bar fitting in said opening and having one end engaging with said rail and the opposite end provided with an inclined upper face, means engaging with the said inclined end of said bar for se- 85 curing the same to said tie, and means for locking said bolt in position.

7. In a rail-support, the combination with the rail, of a tie having an opening in the same, a **Z**-shaped clamping-bar fitting in 9c said opening and having one end engaging with said rail and the opposite end provided with an inclined upper face, a bolt on said tie engaging with the said inclined end of said bar for securing the same to said tie, and 95 means engaging with said bolt to lock the same in position.

8. In a rail-support, the combination with the rail, of a tie having an opening in the same, a **Z**-shaped clamping-bar fitting in 100 said opening and having one end engaging with said rail and the opposite end provided with an inclined upper face, a bolt on said tie engaging with the said inclined end of said bar for securing the same to said tie, and a 105 spring-plate on said tie and engaging with said bolt to lock the same in position.

9. In a rail-support, the combination with the rail, of a tie having an opening in the same, a **Z**-shaped clamping-bar fitting in 110 said opening and having one end engaging with said rail and the opposite end provided with an inclined upper face, a bolt on said tie engaging with the said inclined end of said bar for securing the same to said tie, and a 115 plate on said tie having a spring-lip thereon for engaging with the head on said bolt to lock said bolt in position.

10. In a rail-support, the combination with the rail, of a tie having an opening in the 120 same, a **Z**-shaped clamping-bar fitting in said opening and having one end engaging with said rail and the opposite end provided with an inclined upper face, a bolt on said tie en- 125 gaging with the said inclined end of said bar for securing the same to said tie, and a plate on said tie and held in said opening, said plate having a spring-lip thereon for engaging with said bolt to lock the same in position.

11. In a rail-support, the combination with
the rail, of a tie having an opening in the
same, a Z-shaped clamping-bar fitting in
said opening and having one end engaging
with said rail and the opposite end provided
with an inclined upper face, a bolt on said tie
engaging with the said inclined end of said
bar for securing the same to said tie, and a
plate on said tie and having a flange thereon
for fitting in said opening, said plate having a 10
spring-lip thereon for engaging with the head
on said bolt to lock said bolt in position.
- In testimony whereof I, the said GEORGE
M. CÔTÉ, have hereunto set my hand.

GEORGE M. CÔTÉ.
